JESSE T. RICE, OF GRAND RAPIDS, MICHIGAN, ASSIGNOR TO HIMSELF AND
FRANK J. HUBBARD, OF SAME PLACE.

CAR-COUPING.

SPECIFICATION forming part of Letters Patent No. 230,058, dated July 13, 1880.

Application filed May 19, 1880. (No model.)

To all whom it may concern:

Be it known that I, JESSE T. RICE, of Grand Rapids, in the county of Kent and State of Michigan, have invented a new and Improved 5 Car-Coupler, of which the following is a specification.

The invention consists of a draw-head having circular socket, socket-offset, and spring-socket, in combination with a coupling-hook 10 having circular lower end, shoulders, and spring-socket, a spiral spring, and U-shaped pivots, as hereinafter described.

Figure 1 is a plan of the device, showing the manner of coupling, with a portion broken 15 away to exhibit other parts. Fig. 2 is a front elevation of the device attached to a car. Fig. 3 is a longitudinal sectional elevation of a portion of the device, showing an uncoupling mechanism.

Similar letters of reference indicate corresponding parts.

In the drawings, A represents a car, B the draw-bar attached thereto and carrying the draw-head C, that has within it a circular socket, a, in which the coupling-hook D is pivoted on the vertical pivot b. The inner and pivoted end of this coupling-hook D is of a shape corresponding with that of the socket a, and is provided with an eccentric shoulder, c, 20 that engages in a corresponding recess or offset, n, in said socket a, and thereby holds said coupling-hook from being forced too far forward laterally by the action of the actuating-spring E, and the shape of the inner end of the coupling-hook D and of the socket a prohibits the withdrawal of said coupling-hook D, even should the pivot b break, without first removing the cap C' of the draw-head. A shoulder, f, is formed on the said coupling-hook 25 D, to engage against the front edge of the draw-head C, and prevent said hook D from being drawn or pushed too far back laterally when coupling or uncoupling.

The forward end of the hook D is provided 45 with a coupling-link slot, g, and a coupling-pin opening, h, so that if desired an ordinary link and pin may be used in coupling cars to which this device is applied.

In the back of this coupling-hook D is a 50 curved socket, k, opening opposite and corresponding with a curved socket, l, formed in the draw-head C, and in these sockets k l, extending from one into the other, is the spiral spring E, that operates to throw the end of the

coupling-hook D laterally forward and to hold 55 it coupled.

For the purpose of uncoupling the car the hook D is connected with the brake-rod F by means of the cord or chain G, so that by turning said rod F the brakeman may uncouple 60 the cars, and by reversing the movement may brake the car-wheels.

The pivot b, being formed in U shape, is also made to serve as a means for uncoupling the cars from the sides thereof. One end or 65 leg of the said pivot b is passed down through the cap C' of the draw-head C, through the coupling-hook D, and into the bottom of the said draw-head C, thereby serving, as before said, as a pivot for the hook D, and that portion of 70 the said pivot b that is above the cap C' is bent downward, and the short leg or end thereof is entered through the slot m in the cap C' and down into the recess n, and against the square face of the shoulder c of said coupling-pin, as indicated in Figs. 2 and 3, so that when this short leg of the pivot b is laterally moved to press against the shoulder c the outer end of coupling-hook D is thereby moved against the tension of the spring E. 80 In order to uncouple the cars by means of this pivot b, one end of the rod or lever H is looped around the short leg of the said pivot just above the cap C', and the other end of said rod or lever H, inclining upward at an angle 85 of about forty-five degrees is entered into a socket, o, in one arm of the rocking beam or lever I, that is pivoted horizontally on the front of the car A, so that by moving said socketed arm of said lever I down from either side of 90 the car the work of uncoupling is performed.

Having thus described my invention, what I claim as new, and desire to secure by Letters Patent, is—

1. A car-coupler, constructed substantially 95 as herein shown and described, consisting of draw-head C, provided with circular socket and socket-offset a n, respectively, and curved socket l, coupling-hook D, having circular lower end, shoulders c f, and curved socket k, spiral 100 spring E, and U-shaped pivot b, as set forth.

2. As a means for uncoupling the hook D, and in combination therewith, the bent pivot b, inclined lever H, and rocking lever I, substantially as herein shown and described.

Witnesses: JESSE T. RICE.

FRANK MOULTON,
E. M. HAYS.
